UNITED STATES PATENT OFFICE.

FRED A. PUTNAM, OF MELROSE, AND CHARLES F. ROBBINS, OF ABINGTON, MASSACHUSETTS, ASSIGNEES TO MARKEM MACHINE COMPANY, OF BOSTON, MASSACHUSETTS, A CORPORATION OF MASSACHUSETTS.

TYPE-CARRIER AND MARKING-MACHINE.

1,131,866.

Specification of Letters Patent. Patented Mar. 16, 1915.

Application filed July 2, 1914. Serial No. 848,680.

To all whom it may concern:

Be it known that we, FRED A. PUTNAM and CHARLES F. ROBBINS, citizens of the United States, and residents of Melrose, county of Middlesex, State of Massachusetts, and Abington, county of Plymouth, State of Massachusetts, respectively, have invented an Improvement in Type-Carriers for Marking-Machines, of which the following description, in connection with the accompanying drawing, is a specification, like characters on the drawing representing like parts.

This invention relates to marking and printing machines of that type which include a printing head having a plurality of type members thereon and which has associated with the printing head an auxiliary type plate carrying additional type.

A machine of this general description is illustrated and described in a co-pending application filed by Fred A. Putnam and Charles F. Robbins, Se. No. 848,679 filed July 2, 1914, and in order to illustrate this invention it has been shown as it might be applied to a marking machine of this character. It is to be understood, however, that the invention is not limited to its use in connection with a marking machine of that particular type, but is capable of general use wherever a type carrier is necessary for supporting a plurality of type members.

The object of the invention is to provide a novel type carrier on which interchangeable type members can be placed and firmly held in position and which is constructed so that the type members can be readily removed and replaced by others whenever a change of type is desired.

In order to give a proper understanding of the invention a selected embodiment thereof is illustrated herein which will now be described.

Figure 1 is a sectional view through a printing head of a marking machine such as described in said co-pending application and having the herein-described improvements embodied therein; Fig. 2 is an enlarged section on the line $x-x$, Fig. 1, showing the manner of sustaining the type holder in the type carrier; Fig. 3 is a fragmentary bottom plan view of Fig. 1 with parts broken out;

Fig. 4 is an enlarged perspective view of the type holder; Fig. 5 is a perspective view of one of the type members.

55

1 designates generally a printing head of a marking machine such as shown in said co-pending application and which is provided with a plurality of type members 4 rotatably mounted thereon, each type member being provided with a plurality of type-bearing projections 11, each having formed on its end a type character 12, these type members being capable of adjustment by means of a centering device 13, all as 60 65 described in said application.

In some types of marking machines it is desirable to provide for making a printed impression on two different lines simultaneously. The printed impression on one 70 line can be made by the type members 4 and that on the other line by type characters carried by a type plate. The type plate herein shown is one which is so constructed that the type thereon can be set 75 closely adjacent to those type projections 11 of the type members 4 that are in printing position so that the two lines of the printed impression will be made close together. The printing head 1 has associated therewith a type carrier herein illustrated as constituted by two side pieces 19 that are situated at opposite ends of the printing head and are movably sustained thereby.

This type carrier sustains a type holder 80 which is preferably removably mounted therein, which type holder in turn carries a plurality of interchangeable type members. The type holder is provided with retaining means to lock the type members on 85 the type holder, and this retaining means is in turn locked so long as the type holder is sustained in the type carrier. The type holder herein illustrated comprises two ends or heads 3 and 5 which are connected by a 90 type-carrying bar 6 on which the individual type members 18 are removably mounted. These type members are each provided with the central groove or notch 7 of a size to fit the type-carrying bar 6 and each member can be applied to or removed 95 from the bar. For holding the type members on the type-carrying bar 6 a retaining member 7 is employed which is herein illus-

trated as pivoted to the type bar at one end, as at 8, the other end thereof entering a notch 9 formed in the head 5. When the retaining member 7 is in the position shown 5 in Fig. 4, it engages the sides of the type members 18 and prevents them from being withdrawn from the bar 6. In order to remove the type members the retaining member is swung up into the dotted line position 10 Fig. 4, after which anyone of the type members can be removed from the type bar or new type members can be replaced thereon.

As stated above, the type holder is removably sustained in the two sides 19 of 15 the type carrier and the manner of accomplishing this is such that when the type holder is in the type carrier the retaining member 7 will be locked in its operative position. While any suitable construction 20 capable of operating in this way may be employed, a simple construction is shown in the drawings which has been found to be eminently practicable. The two sides 19 of the type carrier are provided with grooves 25 14 in which the heads 3 and 5 are slidably received, as seen in Figs. 2 and 3, this construction providing means whereby the type holder can be readily withdrawn from or inserted into the type carrier. It will be 30 noted from Figs. 2 and 3 that the end 15 of the retaining member 7 which occupies the groove 9 is situated in the groove 14 of the type carrier when the type holder is in operative position, and by this means the 35 retaining member is locked in its operative position so long as the type holder is in the type carrier.

The construction herein illustrated is such 40 that when the type holder is properly placed in the type carrier the retaining member 7 will abut against those type-bearing projections 11 of the type members 4 that are in printing position, as clearly seen in Fig. 1. This brings the type members 18 closely adjacent to the type 12 from which the impression 45 is made.

For holding the type holder in this position a spring catch 22 is provided in each of the side pieces 19 of the type carrier, said 50 catches being adapted to engage in recesses 23 formed in the heads 3 and 5. These catches are sufficient to hold the type holder in its operative position while permitting the type holder to be readily removed by applying a little pressure thereto.

While the invention has been described as it would be applied to a marking machine of a particular type, yet it will be observed that the invention is of such a character 60 that it can be used in connection with other marking machines, or may be employed generally to hold individual type members in a type carrier whether the type carrier is used in connection with the type members of a printing head or is used by

itself. It is, therefore, intended to cover this form of type carrier and holder, regardless of the particular use to which it is put.

We claim:

1. In a marking machine, the combination 70 with a carrier presenting two side members, of a type holder removably sustained by said carrier and presenting a type-holding bar, and type members embracing and sustained entirely by said bar and removable laterally therefrom, said holder and the type sustained thereby being removable from the carrier as a unit.

2. In a marking machine, the combination 80 with a printing head comprising type disks and means to support the same, of a carrier associated with said printing head and presenting two side members, a type holder removably sustained by the carrier, and type members detachably supported on 85 the holder.

3. In a marking machine, the combination 90 with a carrier presenting two side members, of a type holder removably sustained by said carrier and provided with a type-holding bar, type members embracing said bar and removable laterally therefrom, and a retaining member extending longitudinally of the bar to hold the type members on the 95 holder.

4. In a marking machine, the combination 100 with a carrier provided with two grooved side members, of a type holder slidably sustained in said grooves and provided with a type holding bar, a plurality of interchangeable type members removably mounted on said bar, and a retaining member carried by the holder and extending longitudinally of said bar for retaining the type members in position. 105

5. In a marking machine, the combination 110 with a carrier provided with two grooved side members, of a type holder slidably sustained in said grooves and removable therefrom, a plurality of interchangeable type members removably sustained by said type holder, and a retaining member carried by the holder for retaining the type members in position, a portion of the retaining member being received in one of the grooves in 115 the carrier when the holder is in place whereby the retaining member is locked in position.

6. In a marking machine, the combination 120 with a carrier presenting two grooved side members, of a type holder having two heads slidably received in the grooves of the carrier, and a type-holding bar connecting the heads, interchangeable type members embracing said bar and removable therefrom, and retaining member pivoted to said bar and adapted to engage the type members for holding them in position. 125

7. In a marking machine, the combination 130 with a carrier presenting two grooved side

members, of a type holder having two heads 5
slidably received in the grooves of the carriers, and a type-holding bar connecting the heads, interchangeable type members embracing said bar and removably therefrom, and a retaining member pivoted to said bar and adapted to engage the type members for holding them in position, the free end of said retaining member occupying the groove
10 in one of the side members of the carrier when the holder is in position.

8. In a marking machine, the combination with a printing head having type disks thereon, of a carrier associated with the
15 printing head and presenting two side members, a type holder removably sustained by said carrier and provided with a type-holding bar, and type members embracing said bar and removable laterally therefrom.

9. In a marking machine, the combination 20
with a printing head having type disks thereon, of a carrier associated with the printing head and presenting two side members, a type holder removably sustained by said carrier and provided with a type-holding bar, type members embracing said bar and removable laterally therefrom, and a retaining member extending longitudinally 25
of the bar for retaining the members in position.

In testimony whereof, we have signed our names to this specification, in the presence of two subscribing witnesses.

FRED A. PUTNAM.
CHARLES F. ROBBINS.
